MARGINAL TERRAIN AMPHIBIOUS VEHICLE

John A. Plessinger, Montgomery County, Ohio
(1725 Wesleyan Road, Dayton, Ohio 45406)

Filed Aug. 28, 1969, Ser. No. 18,893

Term of patent 14 years

Int. Cl. D12—13

U.S. Cl. D14—3

FIG-1

FIG-2

FIG-3

FIG-4

FIG-5

FIG. 1 is a perspective view of a marginal terrain amphibious vehicle embodying my new design.

FIG. 2 is a plan view of the marginal terrain amphibious vehicle illustrated in FIG. 1.

FIG. 3 is a side elevational view of the marginal terrain amphibious vehicle illustrated in FIG. 1.

FIG. 4 is a rear elevational view of the marginal terrain amphibious vehicle illustrated in FIG. 1.

FIG. 5 is a front elevational view of the marginal terrain amphibious vehicle illustrated in FIG. 1.

I claim:

The ornamental design for a marginal terrain amphibious vehicle, as shown.
